MAGNETIC RECORDER AND TRANSCRIBER

Theodore F. Schwartz, 11660 St. Andrews Way, Scottsdale, Ariz., and Carl R. Heldt, 320 S. Country Club Drive, Tucson, Ariz.

Filed May 31, 1963, Ser. No. 75,140

Term of patent 14 years

(Cl. D26—14)

FIGURE 1 is a front perspective view of a magnetic recorder and transcriber showing one form of our new design with the cover of the recorder and transcriber in open position, wherein said cover is hinged at the rear upper portion of the recorder and transcriber and when in open position exposes a forwardly and downwardly slanting speaker grill housing, which has a curved wall adjacent the turntable behind which grill housing a tone arm is pivoted and extends in angular position substantially diagonally of the rectangular form of the recorder and transcriber to a position over a circular record disc disposed at substantially an opposite end of the recorder and transcriber from the downwardly and forwardly slanting speaker grill housing;

FIGURE 2 is a fragmentary end perspective view of the form shown in FIGURE 1, a portion of the cover being broken away and omitted for convenience in illustration;

FIGURE 3 is a front perspective view of a magnetic recorder and transcriber, showing another form of our new design with its cover open wherein the cover is hinged to the rear portion of the recorder and transcriber near an upper portion thereof, and when open exposing a forwardly and downwardly slanting speaker grill housing which has a straight wall adjacent the turntable and behind which grill housing a tone arm is located and disposed in substantially diagonally disposed position and extending over a circular record disc at an opposite end of the transcriber and recorder from said speaker grill housing; and

FIGURE 4 is a fragmentary end perspective view of the form shown in FIGURE 3, a portion of the cover being broken away and omitted for convenience in illustration.

The generic features of the design of the invention which are included in both forms disclosed comprises the forwardly and downwardly slanted grille which is exposed when the cover of the transcriber and recorder is in open position. The generic design also includes a tone arm having one end disposed behind the grille between the elevated portion thereof and the hinged portion of the cover, said tone arm extending substantially diagonally with respect to the upper portion of the transcriber and recorder and extending over a circular record disc which is disposed substantially at an opposite end of the transcriber and recorder from the forwardly and downwardly slanted grille; each design also including openings near the corners of the transcriber and recorder in the vertical sides thereof and adjacent the end in which the forwardly and downwardly slanted grille is disposed.

We claim:

The ornamental design for a magnetic recorder and transcriber, substantially as shown and described.
